CLAIM

The ornamental design for a tote bag with compartment, as shown and described.

DESCRIPTION

FIG. 1 is a perspective view of a tote bag with compartment, showing the new design;

FIG. 2 is a front elevation view thereof;

FIG. 3 is a rear elevation view thereof;

FIG. 4 is a left side elevation view thereof;

FIG. 5 is a right side elevation view thereof; and,

FIG. 6 is a top view thereof.

The broken lines in the figures depict portions of the tote bag with compartment that form no part of the claimed design.
